UNITED STATES PATENT OFFICE.

HENRY W. SIMS, OF DALLAS, TEXAS.

REVOLVER SUPPORTING AND OPERATING APPARATUS.

1,018,015.

Specification of Letters Patent.

Patented Feb. 20, 1912.

Application filed June 8, 1911. Serial No. 631,929.

To all whom it may concern:

Be it known that I, HENRY W. SIMS, citizen of the United States, residing at Dallas, in the county of Dallas and State of Texas, have invented certain new and useful Improvements in Revolver Supporting and Operating Apparatus, of which the following is a specification.

This invention relates to new and useful improvements in revolver supporting and operating apparatuses.

The object of the invention is to provide an apparatus designed to be located near a door and comprising a plurality of revolvers mounted to be fired through the door-way after the door has been opened.

Among the particular features of the invention, are, an adjustable support for the revolvers arranged to be moved to different heights from the floor and fastened in position and to be tilted to permit shooting at various angles; counterbalancing weights whereby the support may be operated from one end; a device for simultaneously firing the revolvers; and a shield behind which the operator may stand.

A still further object of the invention is to provide a device of the character described that will be strong, durable, efficient, and simple and comparatively inexpensive to construct, also one in which the several parts will not be likely to get out of working order.

With the above and other objects in view the invention has relation to certain novel features of construction and operation, an example of which is described in the following specification and illustrated in the accompanying drawings, wherein:

Figure 1 is a perspective view showing the apparatus installed in an express car, Fig. 2 is a view of the apparatus partly in section and partly in elevation, Fig. 3 is a transverse vertical sectional view, and Fig. 4 is a detail of the sleeves.

In the drawings the numeral 1 designates a pair of tubular standards which are shown secured in floor flanges 2 attached to the floor and roof of an express car. These standards are positioned so as to stand a little to the side of each side of the car door 3 and are placed a short distance from the door.

Sleeves 4 and 5 embracing the standards are slidably thereon and have provision for rotatively supporting a horizontal bar or

member 6 extending between the sleeves. The sleeve 5 has locking notches 7 adapted to receive the end of a spring pressed adjusting lever 8 mounted on the bar 6 near 60 said sleeve. Transversely of the bar and at intervals, revolvers 9 are fastened with their barrels directed toward the door. By depressing the lever 8 and rotating the bar the revolvers may be tilted up or down or 65 brought to a substantially level position, the notches 7 receiving the lever and locking the bar in the desired position.

From each sleeve a flexible connection 10 extends upward and passes over a pulley 70 14 mounted in the upper end of the standard. This connection passes down into the standard and is attached to a counter balancing weight 11 in the standard, there being a connection and weight for each 75 standard. These weights are made substantially equal to the weight of the bar 6 and its load so that the operator may grasp the bar at one end and raise and lower the same. 80

For fastening the bar 6 at various heights a tube 12 has its ends secured in the sleeves and extends under the bar. In this tube spring pressed plungers 15 are arranged so as to extend through the sleeves and engage 85 in recesses 16 in the standards. These recesses are provided at various points vertically of the standards. One of the plungers is comparatively short while the other is long. This permits thumb pieces 17 secured 90 on the ends of the plungers and projecting through a slot 18 in the under side of the tube, to be located near the sleeve 5 and adjacent the adjusting lever 8.

For operating the revolvers a crank shaft 95 19 is supported on the inner side of the bar 6 and is provided with a lever 20 adjacent the sleeve 5. The cranks 21 of said shaft are disposed in the trigger guards of the revolvers so as to stand in front of the 100 triggers 22 as shown in Fig. 3. When the lever 20 is swung away from the bar the cranks 21 engage and force the triggers rearward thus simultaneously firing all of the revolvers. The lever 20 may be worked 105 back and forth as many times as it is desired to fire the revolvers and where automatic pistols are used the said lever may be held in the rearward position if it is desired to operate the pistols continuously. 110

For protecting the operator a vertical shield 23 is hinged to the side of the car

adjacent that standard carrying the sleeve 5. This shield is swung out at right angles to the side of the car and is provided with peep holes 24 through which the operator 5 may look. It will be noted that the shield is located so that the operator may reach around the inner side thereof with his left hand, the operating parts being located near the sleeve 5 so as to be readily grasped by 10 the left hand. This arrangement leaves the right hand free for other uses.

When at stations or when it is not desired to have the apparatus in position for use the plungers may be withdrawn from the recesses 16 and the bar 6 moved up the standards to a position above the door where it 15 may be fastened by releasing the plungers. A guard plate 25 secured to the under side of the bar 6 and extending toward the stocks 20 of the revolvers protects the apparatus from injury by articles passed through the doorway when the apparatus is elevated. The shield may also be swung back against the wall of the car, all parts thus being out of 25 the way.

When it is desired to place the parts in position for action the shield is swung out and the bar lowered to the desired point and the bar tilted if desired. If an attempt is 30 made to hold up the car the operator merely has to open the door, walking behind the door as he slides the same. After the door is opened the operator steps behind the shield and is in position to operate the apparatus.

What I claim, is:

1. In an apparatus of the character described, a pair of standards, a rotatable transverse support extending between the 40 standards and slidable vertically thereon, a fastening device mounted at one end of the support, a locking device positioned on the

support so as to engage the standards, a plurality of revolvers mounted on the support, and a revolver operating device mounted on the support. 45

2. In an apparatus of the character described, a pair of standards, sleeves slidable on the standards, counter balancing weights connected to the sleeves, a transverse bar 50 rotatably mounted in the sleeves, a plurality of revolvers secured on the bar, an adjusting lever mounted on the bar and engaging with one of the sleeves, spring pressed plungers mounted between the sleeves and engaging the standards, and a revolver operating member mounted on the bar and having a lever at one end. 55

3. In an apparatus of the character described, a pair of tubular standards, sleeves 60 slidably mounted on the standards, pulleys mounted at the upper ends of the standards, counter balancing weights disposed in the standards, flexible connection between the sleeves and the weights passing over the 65 pulleys, a transverse bar between the standards rotatably mounted in the sleeves, one of said sleeves having notches, an adjusting lever mounted on the bar and engaging with the notches of said sleeve, a plurality of 70 revolvers mounted on the bar transversely thereof, spring pressed plungers mounted under the bar and engaging the standards, a crank shaft mounted on the bar and having its cranks in position to engage the triggers of the revolvers, and a lever at one end 75 of the crank shaft.

In testimony whereof I have signed my name to this specification in the presence of two subscribing witnesses.

HENRY W. SIMS.
